UNITED STATES PATENT OFFICE

RAYMOND G. F. LOEWY, OF JACKSON HEIGHTS, NEW YORK

DESIGN FOR A COMBINED AUTOMOBILE BODY AND HOOD

Application filed September 13, 1928. Serial No. 28,127. Term of patent 7 years.

To all whom it may concern:

Be it known that I, RAYMOND G. F. LOEWY, a citizen of the Republic of France, residing at Jackson Heights, Long Island, county of Queens, State of New York, have invented a new, original, and ornamental Design for a Combined Automobile Body and Hood, of which the following is a specification, reference being had to the accompanying drawing, forming part thereof.

Figure 1 is a side elevation view of a com-

bined automobile body and hood showing my new design.

Fig. 2 shows a top plan view of the same.

The stippling represents a different color, although no particular color.

I claim:

The ornamental design for a combined automobile body and hood as shown.

In testimony whereof, I have affixed my signature to this specification.

RAYMOND G. F. LOEWY.
